L. O. WHITE,
SANITARY LAVATORY COVER,
APPLICATION FILED JAN. 15, 1917.

Patented Aug. 14, 1917.

UNITED STATES PATENT OFFICE.

LEON O. WHITE, OF HENDERSON, NORTH CAROLINA.

SANITARY LAVATORY-COVER.

1,236,798.

Specification of Letters Patent. Patented Aug. 14, 1917.

Application filed January 15, 1917. Serial No. 142,482.

To all whom it may concern:

Be it known that I, LEON O. WHITE, a citizen of the United States, residing at Henderson, in the county of Vance and State of North Carolina, have invented certain new and useful Improvements in Sanitary Lavatory-Covers, of which the following is a specification, reference being had therein to the accompanying drawing.

10 This invention relates to a toilet seat cover and has for its object the production of a cover formed from a single sheet of paper or other material, which is specially constructed to prevent a splash while the 15 bowl of the toilet is being used.

Another object of the present invention is the production of an efficient seat cover, which will be automatically removed from the seat of the toilet as soon as the toilet is 20 flushed.

With these and other objects in view this invention consists of certain novel constructions, combinations and arrangements of parts as will be hereinafter more fully described and claimed.

In the drawings:

Figure 1 is a vertical section through the lavatory.

Fig. 2 is a section taken on line 2—2 of Fig. 1.

Fig. 3 is a plan view of the lavatory seat cover.

Fig. 4 is a plan view of the blank from which the lavatory seat cover is formed.

Fig. 5 is a detail perspective of the lavatory seat cover.

Fig. 6 is a section taken on line 6—6 of Fig. 3.

Fig. 7 is a plan view of a modified form 40 of the lavatory seat cover.

By referring to the drawings, it will be seen that 1 designates the lavatory bowl which is provided with the usual seat 2. The present invention has a special reference to a lavatory seat cover which is indicated by the numeral 3 and illustrated in detail perspective in Fig. 5. This cover 3 is preferably formed from a blank sheet of tissue paper or other suitable pliable material which may be found advisable for use. The cover is formed from a blank sheet of material and is provided near the center thereof with a spirally cut strip or ribbon 4 as illustrated clearly in Figs. 3, 4 and 5 of the drawings. The forward portion of the body 3 is provided with a folded trans-

versely extending strip 5 and a dove-tail tongue 6 is cut from the outer forward edge of the strip 5 and this strip 5 is adapted to be folded back upon the body 3 and the tongue 6 is then folded up through the aperture 7 formed by the cutting of the ribbon or strip 4 from the body 3. This structure is clearly illustrated in detail in Fig. 6 of the drawings. It should be understood that the dove-tail tongue 6 by being fastened in the manner set forth, will constitute an efficient reinforcement for the forward or front portion of the side portion just at a point where the greatest strain takes place.

As clearly illustrated in Figs. 1 and 2 of the drawings, which show the device in a position for actual use, it will be seen that the ribbon or strip 4 of the paper which is spirally cut from the sheet 3 extends down into the bowl and the shoe 8 of the spiral ribbon or strip 4 is adapted to rest upon the surface of the water 9 placed within the bowl 1. It should be understood, however, that the spiral ribbon or strip 4 may extend from any portion of the outer circumference of the aperture 7 without departing from the spirit of the invention, for it is not absolutely necessary that the spiral ribbon or strip 4 should extend from one side of the aperture such as illustrated in Fig. 5, although it is preferable to have the device constructed in accordance with the illustration disclosed in Fig. 5 of the drawings. It should be further understood that the shoe 8 is adapted to fit directly under the center of the opening 10 formed in the seat 2 and for this reason will prevent the splash within the bowl 1. It should be further understood that owing to the construction of the spiral ribbon or strip 4, the flushing of the bowl will cause the seat cover to be automatically drawn into the bowl and be easily discharged therefrom for the reason that the water will flush the bowl and will climb up the spiral ribbon or strip 4 and pull the cover 3 down into the bowl.

As illustrated in Figs. 3 and 4 of the drawings, the body 3 may be provided with a perforated or scored line 11 extending across the rear of the strip 4 so as to cause the same to be readily torn or ripped as soon as the bowl is flushed, thereby tearing the seat cover into one narrow strip for facilitating the discharge of the cover through the outlet of the bowl.

As shown in Fig. 7 of the drawings, the

spiral tongue 4' may be formed rectangular or in any suitable or desirable shape and it should be understood that where the term spiral ribbon or strip is employed in the following claims, that it is intended that the term should cover a tongue, ribbon or strip which is spirally constructed whether the same should be formed substantially rectangular or substantially circular.

10 It of course, should be understood that these covers may be supported prior to use within any suitable or desired receptacle or may be mounted in a padlike form.

What is claimed is:

15 1. As a new article of manufacture, a sanitary toilet seat cover formed of a single piece of pliable material provided with a spirally cut strip formed from said body and adapted to hang below said body.

20 2. As a new article of manufacture, a sanitary toilet seat cover formed from pliable material and provided with a tongue cut spirally therefrom and adapted to hang below the normal level of said cover.

25 3. A sanitary toilet seat cover formed from pliable material and provided with a spirally cut strip adapted to hang below the normal level of said cover, the lower end of said strip adapted to rest upon the water

30 carried within the toilet bowl, and said cover provided with a reinforced forward end.

35 4. A sanitary toilet seat cover formed from pliable material and provided with a spirally cut strip adapted to hang below the normal level of said cover, the lower end

of said strip adapted to rest upon the water carried within the toilet bowl, said cover provided with a transversely extending reinforcing strip bent backwardly across the front edge of said cover, said transversely extending reinforcing strip provided with a dove-tail tongue cut therefrom, and said dove-tail tongue being bent backwardly upon said body and extending through the aperture formed by the cutting of said spiral strip from said cover for firmly holding said reinforcing strip in a set position.

5. A sanitary toilet seat cover formed from pliable material and provided with a spirally cut strip adapted to hang below the normal level of said cover, the lower end of said strip adapted to rest upon the water carried within the toilet bowl, said cover provided with a transversely extending reinforcing strip bent backwardly across the front edge of said cover, said transversely extending reinforcing strip provided with a dove-tail tongue cut therefrom, said dove-tail tongue being bent backwardly upon said body and extending through the aperture formed by the cutting of said spiral strip from said cover for firmly holding said reinforcing strip in a set position, and said cover provided with angularly extending perforations projecting across the rear end thereof for permitting said cover to be torn into a narrow strip.

In testimony whereof I hereunto affix my signature.

LEON O. WHITE.
